UNITED STATES PATENT OFFICE.

JACOB NIXON, OF WINFIELD, KANSAS.

SULKY-PLOW.

SPECIFICATION forming part of Letters Patent No. 257,971, dated May 16, 1882.

Application filed March 2, 1882. (No model.)

To all whom it may concern:

Be it known that I, JACOB NIXON, of Winfield, in the county of Cowley and State of Kansas, have invented certain new and useful 5 Improvements in Sulky-Plows; and I do hereby declare the following to be a full, clear, and exact description of the invention, such as will enable others skilled in the art to which it pertains to make and use the same.

10 My invention relates to sulky-plows; and its object is to improve the construction of this class of plows, whereby the point of resistance to the draft may be brought close to the team and a direct draft obtained from the shoulder 15 of the team to the center of the draft.

15 A further object of my invention is to provide a sulky-plow with an extended standard and suitable operating-levers and connecting parts, whereby the maximum leverage may be 20 obtained in adjusting and regulating the plow, thus lessening the labor of the driver.

25 A further object of the invention is to improve the construction of the braces, operating-levers, and connecting parts of the plow, whereby complication may be avoided and the manufacture and use of the plow facilitated.

With these ends in view the invention consists in the features of construction and combinations of parts hereinafter fully described, 30 and pointed out in the claims.

In the drawings, Figure 1 is a perspective view of a sulky-plow constructed in accordance with my invention. Fig. 2 is a side elevation of the same with the furrow-wheel removed. Fig. 3 is a detached view of the axle of the plow. Fig. 4 is a similar view of the 35 land-lever. Fig. 5 is a reverse plan view of the plow, and Fig. 6 is a detached view of the draft-frame and its supporting-bracket.

40 A represents the axle of the plow, consisting of the diagonal main portion a and the horizontal arms a' a'' , the latter being arranged parallel with each other at opposite ends of the diagonal portion a .

45 At a central point on the axle A is secured in any suitable manner the seat-support B, carrying a driver's seat, B'.

At about the center of the axle-arm a' is rigidly secured the rear end of the plow-tongue C 50 by a bolt, e, or in any other suitable manner. The outer end of the axle-arm a' is provided with a spindle, a^3 , to receive the furrow-wheel

X, and upon the inner end of the spindle is provided an annular shoulder, a^4 , for a purpose hereinafter described.

55

D represents the mold-board of the plow, and E the landside, the latter being braced to the mold-board by the horizontal brace e and a twisted diagonal brace, e', by means of which the mold-board and landside are held firmly 60 together and securely braced in all directions against the strain upon them in plowing.

F represents the plow-standard, extended above the tongue C, as shown, and firmly secured at its lower end to the landside, at about 65 the center of the latter, and connected by a V-shaped bracket, c', to the inner side of the mold-board.

The inner side of the standard is provided 70 with a guide-loop, G, secured at its upper end to the standard, a little below the upper extremity of the latter, and at its lower end at a point a little below the center of the standard. This guide G embraces the plow-tongue 75 C, and is adapted to be guided on said beam when the plow is raised and lowered.

Upon the outer side of the standard, and at a point preferably about one-third of the length of the same from its upper end, is provided a stud or projection, H, adapted to engage with 80 a hook or stop, H', secured to the outer side of the plow-tongue, adjacent to the standard, and adapted to limit the downward movement of the latter.

To the upper end of the standard F is pivoted 85 one end of a lever, I, the opposite end of which is fulcrumed on the spindle a^3 of the axle.

The standard is also provided with a toggle-connection, J, the forward arm, j , of which is pivoted at its front end to the standard, at about 90 the center of the latter, and at its rear end to the forward end of the rear arm, j' , of the toggle-joint, the latter being perforated at its rear end to fit upon the shoulder a^4 of the axle-spindle a^3 , and provided at its forward end with a 95 laterally-projecting lip or stop, j^2 , against which the forward arm, j , is adapted to bear when the plow is at work.

A link, j^3 , is pivoted at the inner side of the joint of the toggle-connection by the pivot j^4 , 100 which also connects the arms j and j' . The upper end of the link j^3 is pivoted by a pivot, j^5 , to the forward end of the bell-crank lever K, the pivotal point or fulcrum of the latter

being in a bracket, L, secured upon the top of the plow-tongue, near its rear end. This bracket L consists of a horizontal portion, l, adapted to be secured to the tongue C by screws or bolts, 5 the outer upturned side, l', and the inner vertical side, l'', which is notched to constitute the holding-sector of the plow. Between the sides of this bracket L is fulcrumed the handle M of the lever K by a pivot, m, which also serves to 10 secure the handle to the lever. Said handle is also secured to the lever K by one or more bolts or screws, k, above its pivotal point. Upon the inner side of the handle M is arranged the usual hand-lever, N, and connecting-rod and dog to 15 engage the teeth of the sector l''.

The draft-frame of the plow preferably consists of a strip of metal bent to form an outer side, P, the forward cross-brace, P', and ears P², and the inner curved or semicircular side, 20 P³. The rear ends of the sides P and P³ are pivoted, one on either side of the standard F, by a pivot, p, which also secures the arm j of the toggle-connection to the standard, said arm j being held between the standard and arm P 25 of the draft-frame. The inner curved side, P³, of the draft-frame admits of the attachment of a rolling colter to the plow-tongue, the curvature of said side being such that a colter would not be obstructed or come in contact with the 30 frame.

Q Q' represent depending arms, pivoted on either side of the tongue C, adjacent to the draft-frame, by a bolt, q. These arms are adapted to be pivotally secured at their lower 35 ends between the ears P² of the draft-frame by a rod or bolt, R, to support said frame, and upon the rod R is pivoted a clevis, S, by its perforated ears s. The clevis supports by a bolt, T, the coupling T', to which the team is 40 attached.

M² represents a diagonal brace, secured at its forward end to the beam C at a point in rear of the arms Q Q', and at its opposite end to the arm a² of the axle. Upon the outer end of the 45 axle-arm a² is rigidly mounted a land-sector, V, and the said arm is internally threaded to receive a screw-pivot, v, of the bell-crank lever W, the short arm of which is provided with a spindle, w, upon which is mounted the land-wheel X'. The inner side of the lever is provided with a hand-lever, Y, pivoted to the land-lever, and provided with a rod, y, which is guided in a perforated lug, y', of the lever W, and terminates in a dog, y'', adapted to engage 50 the teeth of the sector V.

By the construction of plow as thus described a direct draft is secured from the plow-standard. The plow may be readily drawn backward out of the ground by forcing the 55 lifting-lever backward; and the depth of the furrow and the working position of the plow are regulated by the lever W, to which the land-wheel X' is secured.

By the peculiar construction of axle above 60 described the furrow-wheel is adapted to fol-

low the plow in the furrow, while the land-wheel is projected forward and, with the weight of the driver, takes all weight from the shoulders of the team and evenly balances the plow.

It will be apparent that many slight changes 70 in the construction of the plow may be made without departing from my invention; and hence,

Having fully described my invention, what I claim as new, and desire to secure by Letters 75 Patent, is—

1. In a sulky-plow, the combination, with the tongue provided on one side with a hook or stop, of the plow provided with an extended standard, having on one side a loop-guide, 80 through which the tongue passes, and on its opposite side a std or projection adapted to engage with the stop on the tongue, substantially as set forth.

2. The combination, with the axle, plow-tongue, and extended standard, of the lever I, pivoted at one end to the axle, and at its opposite end to the upper end of the standard, a lifting-lever, and suitable connections for raising and retracting the plow, substantially as 90 set forth.

3. The combination, with the axle, plow-tongue, and plow, the latter being provided with an extended standard, of the lever I, pivoted at one end to the upper extremity of the 95 standard and at its opposite end to the axle, the lifting-lever, and a toggle-connection provided with a stop, and pivoted at its rear end to the axle and at its forward end to the standard at a point above the mold-board of the 100 plow, substantially as set forth.

4. In a sulky-plow, the combination, with the standard and its toggle-connection J, of the draft-frame, substantially as shown, pivoted to the standard at its rear end, while its forward 105 end is suspended loosely from the tongue and adapted to receive the coupling for the team, substantially as set forth.

5. In a sulky-plow, the combination, with the plow-tongue and vertically-moving standard, 110 of the draft-frame pivoted at its rear end to the standard above the mold-board, while its opposite end is supported between swinging arms depending from the tongue, and provided with means for lateral draft adjustments, substantially as set forth.

6. The combination, with the plow-tongue, of a bracket adapted to be secured thereto, and provided with upwardly-projecting sides to receive the lifting-lever, the inner one of said 120 sides being notched to form the holding-sector of the plow, substantially as set forth.

In testimony whereof I have signed this specification in the presence of two subscribing witnesses.

JACOB NIXON.
